R. T. CAMERON

COMB

Filed March 5, 1924

Robert T. Cameron ^{Inventor}
Chas. Williamson
By ^{Attorney}

UNITED STATES PATENT OFFICE.

ROBERT T. CAMERON, OF MEMPHIS, TENNESSEE, ASSIGNOR TO BEAUTY PRODUCTS COMPANY, OF NEW YORK, N. Y., A CORPORATION OF DELAWARE.

COMB.

Application filed March 5, 1924. Serial No. 697,098.

To all whom it may concern:

Be it known that I, ROBERT T. CAMERON, residing at Memphis, Tennessee, a citizen of the United States, have invented certain new and useful Improvements in Combs, of which the following is a specification.

My invention has to do with the treatment of human hair for straightening or dyeing it, etc., and the object of my invention is to provide an instrument or appliance by which a liquid to be applied to the hair may most efficiently be applied and the manipulations required in its use may be most readily performed and a special object of my invention is to provide the appliance with means for heating oil or other liquid which requires heating in the treatment of hair and to heat that portion of the appliance which has contact with the hair in those cases where heating is necessary or desirable. My invention consists in whatever is described by or is included within the terms or scope of the appended claims.

In the drawings I illustrate an embodiment of my invention in which Fig. 1 is a longitudinal section of the appliance;

Fig. 2 is a section on the line 2—2 of Fig. 1;

Fig. 3 is a longitudinal section on line 3—3 of Fig. 2.

Fig. 4 is a detail view of a wickholder that may be used.

Briefly described the embodiment of my invention shown in the drawings has the formation of a comb with teeth of ordinary form in combs for merely combing the hair and which in the part corresponding with the usual back of the comb has two parallel, longitudinally extending chambers one of which is a container or reservoir for oil from which ports or passages pass to the comb teeth and have their exit or discharge ends on the teeth and the other chamber which is situated between the container or reservoir and the comb teeth is a heating chamber, the heating being done by an electric heater placed therein or by some other heat imparting instrumentality so that the heat is applied to the oil in the container or reservoir and to the portions of the comb through which the oil is fed to the teeth, as well as to the teeth.

Referring now in some detail to what is shown in the drawing the comb com-

prising the back, 10, and the teeth, 11, conveniently made in one-piece of glass, brass, aluminum or any other metal or material has at one end a handle, 12, which may be of metal and hollow or in one piece with the rest of the comb, but which if made as a separate piece as shown in the drawings may be attached to a round projection, 13, at one end of the back over which one end of the handle may be slipped and the two secured together by a set screw, 14, or other means. Extending longitudinally of the comb back is a chamber, 15, for oil or other liquid which at its outer end is closed by a removable screw cap, 16, for placing liquid therein and from such chamber ducts or ports, 17, pass whose outlet or discharge ends are at the sides of the teeth of the comb there being preferably although not necessarily such a duct for each tooth. The feed of oil from the container or reservoir may be produced or controlled in various ways. As shown in the drawing a valve device may be employed which consists of a rod, 18, extending through a passage that intersects all of the ducts and which for each duct has a cooperating passage which by a sliding movement of the rod may be placed into or out of alignment with the duct and thus permit the flow of liquid or stop it. Said valve may be held at one limit of its movement to cut off the flow of oil by a coil spring, 180, bearing against one end of the rod, against the pressure of which the rod may be moved to open the valve by a button, 19, on the exterior of the comb.

In the comb back between the liquid reservoir, 15, and the teeth is a longitudinally extending chamber, 20, which is the heat supplying chamber and situated so it supplies heat to the oil in the reservoir and to the oil as it passes through the ducts and to the teeth, said chamber, 20, alining with a longitudinally extending passage, 21, in the handle, 12. Within the heat supplying chamber may be placed the heating element, 22, of an electric heater, the wires from which pass outward through the passage, 21, in the handle, the current being turned on or cut off by a switch, 23, which may be a sliding switch of well known construction on the exterior of the handle, 12. In those cases where electricity is not avail-

able for heating a metal rod first heated on a gas stove, lamp or otherwise may be thrust or inserted into the chamber, 20.

Instead of using a valve to control the flow of oil or liquid from the chamber, 15, a wick or body of absorbent material may be placed in such chamber, 15, saturated with the liquid. In this case (see Fig. 4) a slender rod or wire, 24, may be attached at one end to the screw cap, 160, on which may be wrapped or wound twine or wool or other absorbent material, this being a convenient way of supporting and inserting and removing the wick. In some cases it may be desirable to employ some form of force feed for the oil or liquid and I contemplate providing such a feed.

What I claim is:

1. A hair treating appliance comprising a liquid container and hair engaging means to which liquid may be supplied from such container and heating means comprised in a chamber intermediate said liquid container and said hair engaging means.
2. A hair treating appliance comprising a comb with back and teeth, a liquid hold-

ing chamber in the back, means for conveying liquid from such chamber to the exterior of the teeth and heating means situated in the comb back.

3. A hair treating appliance comprising a comb having back and teeth, the back having two longitudinally extending chambers one of which forms a liquid reservoir and from which ducts lead to the comb teeth, the other chamber being intermediate the liquid chamber and the teeth and adjacent to said ducts and heating means in such other chamber.

4. A hair treating appliance comprising a comb having back and teeth, the back having two longitudinally extending chambers one of which forms a liquid reservoir and from which ducts lead to the comb teeth, the other chamber being intermediate the liquid chamber and the teeth and adjacent to said ducts, and means to control the flow of liquid through such ducts and heating means in such other chamber.

In testimony whereof I hereunto affix my signature.

ROBERT T. CAMERON.
